US00D837803S

(12) **United States Design Patent** (10) **Patent No.:** **US D837,803 S**
Peng et al. (45) **Date of Patent:** **** Jan. 8, 2019**

(54) **PAPER SUPPORT**

(71) Applicant: **AVISION INC.**, Hsinchu (TW)

(72) Inventors: **Chao-Yu Peng**, Hsinchu (TW);
Chi-Yao Chen, Miaoli County (TW);
Hsin-Chen Lee, Hsinchu (TW)

(73) Assignee: **Avision Inc.** (TW)

(**) Term: **15 Years**

(21) Appl. No.: **29/602,651**

(22) Filed: **May 2, 2017**

(51) LOC (11) Cl. **14-02**

(52) U.S. Cl.

USPC **D14/453**

CLAIM

The ornamental design for “paper support”, as shown and described.

DESCRIPTION

FIG. 1 is a top front right perspective view showing our new design;

FIG. 2 is a bottom rear right perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top rear left perspective view of our new design installed on a scanner; and,

FIG. 10 is a top front left perspective view of our new design installed on a scanner.

The broken lines, which illustrate the environmental structure of the claimed design, form no part of the claimed design.

1 Claim, 8 Drawing Sheets
